UNITED STATES PATENT OFFICE.

AARON H. HANDY, OF KANSAS CITY, MISSOURI.

AUTOMATIC PAPER-CUTTING MECHANISM.

1,208,957.

Specification of Letters Patent. Patented Dec. 19, 1916.

Application filed March 6, 1916. Serial No. 82,369.

To all whom it may concern:

Be it known that I, AARON H. HANDY, a citizen of the United States, residing at Kansas City, in the county of Jackson and State of Missouri, have invented certain new and useful Improvements in Automatic Paper-Cutting Mechanism, of which the following is a full, clear, and exact description, such as will enable others skilled in the art to which it appertains to make and use the same.

The invention relates to mechanism for containing rolls of wrapping paper and cutting various lengths from the roll as required.

It is essential that the roll of paper be journaled in suitable frames so that it will roll freely without tearing the paper, and that a suitable brake be provided to check the rolling of the roll when the desired length of paper has been drawn therefrom so that the roll will stop and not unwind more paper than is drawn from the roll. A construction that will admit of employing sheet metal for the cutting knife, and provide for the mounting of a plurality of rolls in one frame is also very desirable.

The present invention seeks to provide an improved mechanism for supporting rolls of paper and automatically cutting desired lengths of paper therefrom, the features of the invention relating more particularly to certain improvements in the mechanism of the machine embodied in United States Patent No. 1,159,837, which was issued to the applicant Nov. 9th, 1915.

A further object of the invention is to provide a suitable adjustable resilient brace that will act direct upon the surface of the roll of paper.

A still further object of the invention is to provide for the mounting of plural rolls of paper and serving them by a single knife constructed of thin sheet metal and to employ an intermediate rest and stop for the knife so that it will not spring and tear the paper.

A still further object of the invention is to provide an improved form of brake upon the small roll near the knife so that the paper when drawn from the mechanism rapidly will immediately stop when the drawing tension ceases and no more paper will be drawn than is desired.

With these and other objects in view the invention consists in the features of con-

struction, shapes, combinations and arrangements of parts hereinafter set forth, illustrated in the accompanying drawings and more particularly pointed out in the appended claims.

In the drawings: Figure 1, is a view of the improved mechanism in elevation, arranged for and containing plural rolls of paper. Fig. 2, is a sectional view of the mechanism taken on line *a—a* of Fig. 1. Fig. 3, is a fragmentary enlarged sectional view taken on line *b—b* of Fig. 1. Fig. 4 is a fragmentary enlarged sectional view taken on line *c—c* of Fig. 1. Fig. 5, is a fragmentary enlarged view. Fig. 6, is a fragmentary enlarged view. Fig. 7 is a view of the mechanism in elevation, arranged for and containing a single roll of paper.

The base 1 is preferably of rectangular shape as shown and of wood because of inexpensiveness, the end frames 2 and 3 and the intermediate frame 4 being secured to the base by screws 5 and extending upward therefrom, the journal boxes 6 being preferably integral with the respective frames and open upward so that the rolls of paper 7 may be placed with the journals 8 resting in the boxes as shown and removed therefrom without manipulating any part of the mechanism.

Secured to the base 1 and opening upward and provided with the flanges 9 along the upper edge thereof is the channel shaped guide 10, the flanges extending toward each other and then projecting downward in the form of teeth 12, forming a trackway between the toothed flanges and the bottom 13 of the guide for the spring 14. The spring 14 has a wide portion 15 which rests upon the bottom 13 at the end 16 thereof, and upwardly inclined integral pawls 17 which engage the teeth 12, the spring being free to slide along the channel shaped guide 10 when the end 18 thereof is pressed downward and the pawls released from the teeth, the tension of the spring produced by the end 19 bearing upon the roll of paper 7 always holding the pawls securely in engagement with the teeth.

From the foregoing it will be understood that the end of the spring 18 can be pressed downward and the pawls 17 released from the teeth 12, and the spring easily moved along the channel shaped guide 10 until the end 19 of the spring has the desired brake tension on the roll 7, which tension will de-

pend on the swiftness with which the paper is withdrawn from the roll, and that when the end 18 is released the tension of the spring by reason of the end 19 bearing upon 5 the roll 7, will press the pawls 17 into engagement with the teeth 12 and the spring will remain in this position until readjusted, the shape of the spring producing more brake tension when the roll is of full size 10 than when the paper is more nearly removed, this being desirable as the more paper the more weight and the greater the inertia that must be checked and stopped.

The roll of paper 7 is wound upon the 15 roller 21 which is provided with projecting journals 8 to fit and revolve freely in the journal boxes 6.

The roller 23 is provided with projecting journals 26 which are journaled in the end 20 frames 2 and 3 so that the roller will freely revolve, the journals extending through the slots 45 in the slotted arms 27, the arms being pivoted to the frame at 28, and having secured thereto the covered sheet metal guide 25 29 which also serves as a brake.

Above the slotted arms 27 are the irregularly T shaped arms 30 which are pivoted at 31 to the end frames 2 and 3, these T shaped arms terminating in three projecting 30 arms 32, 33 and 34, the arms 32 extending to the pivoted points 31, the arms 33 having secured to the bottom thereof the flat sheet metal guide 35, and the arms 34 extending over and always bearing upon the portions 35 46 of the slotted arms 27 and holding the curved sheet metal guides 29 and the flat sheet metal guide 35 in close proximity to each other.

The curved sheet metal guide 29 is separated 40 from the flat sheet metal guide only by the sheet of paper 11 and is provided with the slot 20 through which the paper is threaded, the side of the guide 29 being so curved as to fit over the roller 23 along 45 the side nearest the flat sheet metal guide 35 and form a brake as hereinafter will appear.

The arm 36 is secured to the flat sheet metal guide 35 intermediate the arms 30 and is pivoted in the bifurcated jaw 37 50 at 38, so that the end 39 thereof will bear against the jaw at 40 when the arms 35 and 36 are in the extreme upward position as will appear in the description of the operation, hereinafter, the jaw 37 being secured 55 to the frame tie piece 41 by the integral bolt 42, the tie piece being secured to the end frames 2 and 3 by the screws 43. The arm 36 is for the purpose of supporting the flat sheet metal guide 35, the latter serving also 60 as a knife to sever the paper by an upward pull thereon when the desired length has been withdrawn from the roll 7, the arm being employed only when the sheet metal guide and knife is of a long length, as in 65 connection with long rolls for wide paper

and in connection with the mounting of two or more rolls under the same knife, it being desirable under certain conditions to mount several rolls 7 under the same knife, especially when the paper is of a narrow width. 70

The paper 11 is wound upon the roller 21 and placed with the journals 8 in the boxes 6 after which the paper is threaded over the roller 23 and under the curved portion 25 of the curved sheet metal guide 29 until the slot therein 20 is reached, the paper passing upward through this slot and then outward between the flat portion of the curved sheet metal guide 29 and the flat sheet metal guide 35, the paper in normal position always protruding from the guides sufficiently to allow of gripping it to withdraw from the roll 7, the normal position of the guides and supporting arms and paper being illustrated in Fig. 2.

When it is desired to remove a length of paper from the roll the paper 11 is grasped near the guides 29 and 35 and drawn outward until the desired length extends from the guides, when an upward pull on the paper will instantly throw the parts of the mechanism to the position illustrated in Fig. 3 the edge 44 of the guide 35 serving as a knife and severing the paper. After the paper is severed the mechanism immediately assumes the position shown in Fig. 2 and the paper is extended as illustrated in this view, it being obvious that the paper is always in a position to allow of gripping it by the hand and that but an instant is required to withdraw and sever any desired length of the paper.

The frames 2 and 3 are each offset and extended outward at 47 in order to secure a greater distance between the frames and admit of the guides 29 and 35 being extended to a greater width, this feature serving to allow the paper to be withdrawn at a considerable angle from a right angle from the axis of the roll 7, so that the operator will 105 not be required to notice whether the paper is drawn at a right angle from the rolls, it being obvious that the person desiring wrapping paper is usually in a hurry and will draw and cut the paper without looking at 110 or thinking of the paper cutting mechanism or the roll of paper, the mind being occupied by other matters.

In Fig. 7, the mechanism is arranged for and contains but one roll of paper 7^a, the 120 construction differing from that hereinbefore described only in that the frame 4 arm 36 bifurcated jaw 37 and one spring 21 and accompanying parts are omitted and the base 1^a and frame tie 41^a are shorter than 125 the base 1 and frame tie 41.

The automatic paper cutting mechanism is of chief importance for the containing rolls of paper and cutting and serving it in the desired length, but may also be advan- 130

tageously employed for the serving of toilet paper and the like.

I claim:

1. In paper cutting mechanism, a base, a frame rising from said base adapted to support a roll of paper journaled in said frame, a spring slidably mounted in said base, said spring curving upward and engaging said roll of paper, said spring adjustable transversely of said base, means to lock said spring in the desired location, and means to cut lengths of paper from said roll.
2. In paper cutting mechanism, a base, a frame rising from said base adapted to support a roll of paper journaled in said frame, a guide arranged transversely of said base, a spring arranged to traverse said guide and contact with said roll of paper, said spring slidable in said guide, teeth in said guide, said spring arranged to engage said teeth by the resiliency of said spring, and means to cut lengths of paper from said roll.
3. In paper cutting mechanism, a frame adapted to support a roll of paper journaled in said frame, a roller journaled in said frame above said roll of paper, slotted arms pivoted adjacent said roller, the journal of said roller passing through said slots, said arms projecting outward from said roller, a sheet of metal secured to said arms and formed in segmental shape over said roller, said sheet of metal having a flat portion extending outward from said roller, a slot longitudinally of said flat portion of said piece of metal whereby the paper from said roll may pass over said roller and upward through the slot in said flat portion, and project outward over and from said flat portion, arms pivoted above said roller, a flat piece of sheet metal serving as a knife and secured to said latter arms and said flat

piece of metal resting upon the paper and severing said paper when said paper is drawn upward.

4. In paper cutting mechanism, a frame 45 adapted to support a roll of paper journaled in said frame, a roller above said roll of paper and journaled in said frame, lower arms pivoted adjacent said roller, upper arms pivoted above said guide paper while 50 being drawn from said roll, a sheet metal brake to contact with paper on said roll, an upper sheet metal guide, and said upper sheet metal guide serving as a knife to sever the paper.

5. In paper cutting mechanism a frame adapted to support a roll of paper journaled in said frame, a roller journaled in said frame, arms pivoted adjacent said roller, sheet metal guides on said arms to guide paper drawn from said roll of paper, a sheet metal brake on said arms to engage the paper on said roller, and one of said sheet metal guides serving as a knife to sever the paper.

6. In paper cutting mechanism, a frame comprising end frame members, paper guides, a paper cutting knife, said frame members offset and extended outward providing room for said paper guides and paper cutting knife, said guides and said knife of considerable greater length than the distance over rolls of paper journaled in said frame, and said cutting knife adapted to cut lengths of paper from said roll of paper.

In testimony whereof I affix my signature in the presence of two witnesses.

AARON H. HANDY.
